UNITED STATES PATENT OFFICE.

HARMON E. LINDBLADH, OF BOSTON, MASSACHUSETTS.

INDICATING MECHANISM FOR FEEDING APPARATUS.

1,258,027.

Specification of Letters Patent.

Patented Mar. 5, 1918.

Original application filed June 25, 1913, Serial No. 775,737. Divided and this application filed July 2, 1917.
Serial No. 178,085.

To all whom it may concern:

Be it known that I, HARMON E. LINDBLADH, a citizen of the United States, residing at Boston, in the county of Suffolk and 5 State of Massachusetts, have invented a new and useful Indicating Mechanism for Feeding Apparatus, of which the following is a specification.

This invention relates to sheet-feeding apparatus such as that of my co-pending application Serial No. 775,737, filed June 25, 1913, and particularly concerns means for indicating to the attendant the delivery of a definite number of sheets, thereby relieving 10 said attendant of the necessity of keeping close watch upon the operation of the apparatus. Sheets are ordinarily separated after being acted upon by the machine to which the feeder delivers into bundles containing 15 a particular number. It is customary, for example, for the operators of ruling machines to separate the successive reams of paper on the table of the feeder by slips of paper, and if they observe when these 20 slips are reached they can remove the ruled sheets in bundles of 500 each. It is difficult for the attendant to give this matter the necessary attention and too many sheets are frequently fed and bundled. The indicating 25 mechanism which will now be described prevents this. In accordance with the invention, simple and accurate mechanism is provided for giving an audible signal upon 30 passage of the last sheet of a predetermined group to be fed and for marking said sheet to identify it.

The accompanying drawing, in which the same reference characters designate like parts throughout, illustrates the invention 35 in connection with the feeder described in detail in the above mentioned application, Figure 1 being a top plan view and Fig. 2 a sectional elevation looking from the right in Fig. 1. It will be understood, however, 40 that my improved indicating mechanism may be employed with any suitable feeder.

At F is shown a portion of the frame of an apparatus for feeding sheets of such material as paper from a pile S supported upon 45 a table T. The delivery of the sheets is controlled by retaining and advancing devices R and A, respectively, the latter being rotated by a shaft 55 driven from some suitable source of power. Fixed to the shaft 55 50 just inside one of the standards of the frame

F is an actuating finger or projection 97 co-operating with the teeth of a wheel 98 mounted upon the standard, these teeth being illustrated as twenty in number. At the periphery of the wheel is a projection 99 60 adapted to engage any one of the teeth in a wheel 100 fixed to rotate in proximity to the wheel 98. The wheel 100 is shown as having twenty-five teeth. Both wheels, while turning loosely on their supports, may 65 be held against too free rotation by any desired means, as by the pressure of springs 101. It will be seen that after the finger 97 has engaged the teeth of the wheel 98 twenty times as a result of this number of turns of 70 the device A and the consequent feeding of twenty sheets, the projection 99 will have been moved through three hundred and sixty degrees; so that once in each complete rotation of the wheel 98 it will engage a 75 tooth of the wheel 100, and after five hundred revolutions of the projection 97, or a number corresponding to the sheets in a ream, the wheel 100 will have been advanced a full turn. The use of two wheels thus 80 proportioned is to avoid the employment of a wheel having five hundred teeth, which would be of excessively large diameter.

On the wheel 100, here illustrated as being on opposite sides thereof, are projections 85 102 and 103. The projection 102 engages an arm 104 depending from a lever 105 fulcrumed above the wheel 100, and normally drawn against a stop 106 by a spring 107. Fixed to the lever 105 is a spring-tongue 90 108 carrying a hammer adapted to contact with a gong or other audible signal device 109. Once in each rotation of the wheel 100, or for five hundred sheets fed, the projection 102 will strike the arm 104, raising 95 the lever from the stop. Then as the projection passes away from the arm, the tensioned lever falling upon the stop will cause the hammer to strike the gong, thus warning the attendant that a ream of paper has 100 been delivered by the feeder. The projection 103 contacts with one arm of a lever 110, the opposite arm of which has an angular end or latch 111 adapted to engage a depression 112 in a wheel 113. This wheel 105 is secured to an oscillatory support or shaft 114 extending across the machine and journaled in brackets carried by the frame F, and has fixed to it an arm 115 upon which 110 is a weight 116 tending to force a pencil or

marking device 117 against the top sheet of the pile. The shaft 114 also carries a second arm or setting member 118, which when the pencil is resting upon the sheet lies in the path of the finger 97. When the gong is struck, as a result of the contact of the projection 102 with its actuating arm, the projection 103 also engages the lever 110, withdrawing the latch 111 from the 10 wheel-depression. This releases the pencil, causing it to mark the last sheet of the ream, thus giving the attendant a visual indication of the delivery of the predetermined quantity. Consequently upon hearing the 15 gong, he may within a suitable time run over the upper sheets of those operated upon by the machine fed, and on finding the marked sheet will be able to remove the unit-bundle. Upon the next revolution of 20 the finger 97 after the trimming of the latch for the marking device, said finger engages the end of the shaft-arm 118 raising the pencil from the paper and allowing the latch to fall back into the depression, the 25 pencil thus being restored to its normal position.

Having thus described my invention, I claim:

1. The combination with feeding mechanism for delivering sheets one by one to a machine which is to operate upon them, of means for applying to a particular one of the sheets after a predetermined number has been fed an identifying mark effective in 30 all positions of the sheets, and means for signaling the operator at the time of marking to enable him to promptly find the marked sheet and remove the bundle containing the predetermined number.
- 40 2. In a sheet-feeder, an audible signal device and a sheet-marking device, and a wheel rotatable in the action of the feeder and having separate projections for operating said devices.
- 45 3. In a sheet feeder, a plurality of projections revolute in the action of the feeder, and a plurality of indicating devices of different character respectively operable by the projections, one of said devices being constructed and arranged to inform the operator that the other device has acted.
- 55 4. The combination with sheet-feeding mechanism, of a marking device normally held out of coöperation with the sheets, means effective after the predetermined number of operations of the feeding mechanism for releasing the marking device to engage a sheet, and means operable by the feeding mechanism for restoring the marking device to its inactive position.
- 60 5. The combination with feeding mechanism, of an indicating device, means for latching the indicating device in an inactive position, means operable by the feeding mechanism for releasing the indicating device, and

means for restoring the indicating device to its inactive position.

6. The combination with feeding mechanism, of an indicating device, means for maintaining the indicating device in an inactive position, and means operable by the feeding mechanism for releasing the indicating device and for restoring said indicating device to its inactive position. 70

7. The combination with sheet-feeding 75 mechanism and an actuating member movable thereby, of indicating mechanism, a marking device for coöperation with the sheets fed, and a setting member and a retaining member for the marking device, the 80 indicating mechanism coöperating with the retaining member and the actuating member coöperating with the setting member.

8. The combination with sheet-feeding mechanism and an actuating member movable thereby, of an oscillatory support situated above the path of the sheets, a marking device movable by the support into contact with the sheets, retaining means for the marking device, and an arm extending from 85 the support and coöperating with the actuating member. 90

9. The combination with sheet-feeding mechanism and an actuating member movable thereby, of an oscillatory support situated above the path of the sheets, a marking device movable by the support into contact with the sheets, retaining means for the marking device, and an arm normally removed from the path of the actuating member but movable into said path of the actuating member when the marking device contacts with the sheets. 95

10. The combination with sheet-feeding mechanism and an actuating member movable thereby, of indicating mechanism, an oscillatory support situated above the path of the sheets and having a member provided with a depression, a latch for engagement with the depression, means operated by the 100 indicating mechanism for withdrawing the latch from the depression, a marking device movable by the support, and means for restoring the engagement of the latch and depression. 110

11. In a sheet-feeder, a rotatable feeding device, a projection rotatable with the feeding device, a wheel engaged by the projection, a projection revolute by the wheel, and an indicating device coöperating with the 115 last-named projection.

12. In a sheet-feeder, a rotatable feeding device, a projection rotatable with the feeding device, a wheel engaged by the projection, a plurality of projections revolute by 120 the wheel, and an indicating device coöperating with each projection.

13. In a sheet-feeder, a rotatable feeding device, a projection rotatable with the feeding device, a wheel engaged by the projec- 125

tion, a plurality of projections revoluble by the wheel, a marking device coöperating with one projection, and an audible signal device coöperating with another projection.

5 14. In a sheet-feeder, a marking device movable by gravity toward the sheets, a latch for normally maintaining the marking device out of coöperation with the sheets, and means effective after a predetermined 10 number of sheets has been fed engaging the latch to release the marking device.

15. In a sheet-feeder, a rotatable feed-

ing device, a finger rotatable with the feeding device, a wheel engaged by the finger, a projection revoluble by the wheel, 15 a normally ineffective indicating device released by the projection, and means engaged by the finger for resetting the indicating device.

Signed at Boston, in the county of Suffolk and State of Massachusetts, this twenty-seventh day of June, 1917. 20

HARMON E. LINDBLADH.
